UNITED STATES PATENT OFFICE.

JOHN JAMES AND ALVIN D. GOODENOUGH, OF HENRIETTA, TEXAS.

SHACKLE.

SPECIFICATION forming part of Letters Patent No. 404,544, dated June 4, 1889.

Application filed December 7, 1888. Serial No. 292,893. (No model.)

To all whom it may concern:

Be it known that we, JOHN JAMES and ALVIN D. GOODENOUGH, citizens of the United States, residing at Henrietta, in the county 5 of Clay and State of Texas, have invented certain new and useful Improvements in Shackles; and we do declare the following to be a full, clear, and exact description of the invention, such as will enable others skilled in 10 the art to which it appertains to make and use the same.

This invention relates to means for shackling prisoners; and it consists in connecting with handcuffs a pair of mittens, in the manner 15 hereinafter specified and claimed.

The novelty will be fully understood from the following description and claims, taken in connection with the accompanying drawings, in which—

20 Figure 1 is a perspective view of the mittens and handcuffs, embracing my improvements, ready to be applied to the hands and wrists of a prisoner. Fig. 2 is a perspective view of one of the handcuffs and wristband 25 for attaching the mitten applied thereto; and Fig. 3 is a perspective view of one of the handcuffs provided with turn-buttons for the direct application of the mittens.

It sometimes occurs that handcuffed prisoners are required to be transported in cold 30 weather from one portion of the country to another at the risk of great suffering and loss of hands. It also sometimes happens that handcuffed prisoners are frantic with anger 35 or insanity and liable to injure themselves or the persons in charge by the fingers of their hands. To remedy these difficulties, we provide a pair of strong mittens, preferably of leather or heavy cloth, and connect them with 40 handcuffs in the manner shown on the drawings, in which A indicates handcuffs, and B mittens. In the wrist of each mitten we form two button-holes c, and preferably surround with a metallic plate. (Marked d.) We further

provide said mittens with straps and buckles 45 e, for purposes of security and convenience in attaching and removing the same.

We usually cover the handcuffs with leather or strong heavy cloth provided with pendent flaps f, as shown on Fig. 2, and arrange buttons on said flaps, as shown at g, which, when on duty, enter the button-holes on the wrist of the mittens, and thereby complete their union between said handcuffs and mittens.

In case the handcuffs are not covered and 55 provided with flaps f, we attach buttons to the handcuffs themselves, in the manner shown in Fig. 3 of the drawings. This mode of attachment is preferable in point of economy, and also in cases where additional warmth is 60 not required for the wearer's wrist.

These handcuffs are provided with the usual lock and key.

It is obvious that mittens formed of any suitable material may be profitably employed 65 in conjunction with handcuffs. Even cloth, yarn, wire, and sheet metal will often be found to meet the requirements of the case; but we usually prefer the use of leather or heavy and strong fabric.

Having described our invention, what we claim is—

1. A mitten provided with button-holes in its wrist, in combination with a handcuff provided with a fastening-button, substantially 75 as specified.
2. A handcuff provided with a flexible wrist band or cuff and carrying devices whereby a mitten may be attached thereto, substantially as specified.

80 In testimony whereof we affix our signatures in presence of two witnesses.

JOHN JAMES.

ALVIN D. GOODENOUGH.
